UNITED STATES PATENT OFFICE

2,647,217

ELECTRIC DISCHARGE LAMP

Ted E. Foulke, Highland Heights, Ohio, assignor
to General Electric Company, a corporation of
New York

Application November 29, 1951, Serial No. 258,911

5 Claims. (Cl. 313—185)

1

By invention relates to gaseous electric discharge lamps generally, and more particularly to ultraviolet lamps of the negative glow type. Still more particularly, my invention relates to negative glow lamps of the type employing a gas filling comprising nitrogen as a source of ultraviolet radiations.

It is an object of my invention to improve the performance of such lamps in respect to such factors as high ultraviolet light emission for a long useful life. It is a further object to obtain high ultraviolet emission and long useful life without adversely affecting the breakdown and operating voltage characteristics of such lamps.

Ultraviolet glow lamps as heretofore constituted have employed a gas filling consisting of argon with 10 to 15 per cent of nitrogen. The life of such lamps has been limited due to "clean up" of the nitrogen. In fact, attempts to make certain small types of such lamps have proved futile because the nitrogen was entirely cleaned up during activation of the electrodes, presumably by combination of the nitrogen with the activating alkaline earth metals usually employed on the electrodes. The use of higher pressures or an increase in the nitrogen content resulted in lamps having a high breakdown and operating voltage, and also resulted in uncertain location and stability of the corona discharge.

In accordance with the present invention, I have found that the difficulties referred to above are eliminated by the addition to the gas filling of a substantial proportion of helium. It seems that with over 5 per cent of helium and a few per cent of nitrogen in a mixture of argon, helium and nitrogen, the nitrogen is not rapidly cleaned up, but is retained for an appreciable time in the gas phase by the presence of the helium. Improved results may be obtained by employing the three components of the gas filling in a wide range, by volume, of 5 to 80 per cent helium, 5 to 15 per cent nitrogen, and the balance argon. For the best maintenance of ultraviolet output at the lowest voltage I prefer a range of 5 to 15 per cent nitrogen, 15 to 35 per cent helium and the balance argon. With one type of lamp containing an optimum composition of 65 per cent argon, 25 per cent helium and 10 per cent nitrogen, I have obtained a useful ultraviolet output for a life three times as long as that obtained with otherwise similar lamps containing, at the same pressure, the argon-nitrogen mixture with no helium. In the case of certain other very small lamps, wherein the results were entirely negative when employing the argon-nitrogen mixture be-

2

cause of clean up of nitrogen, I have obtained a useful life in excess of 100 hours by the addition of helium.

I have found, in general, that the higher content of helium in the mixture gives higher absolute ultraviolet output per unit of current, although the breakdown voltage of the lamp rises. While the increased voltage may limit the use of higher helium contents in lamps operating on commercial circuits having a fixed voltage, such as the conventional 105-125 volt circuits, the increased ultraviolet output may be availed of in special circuits. For operation at lowest voltage together with good ultraviolet maintenance, I prefer to employ a content of helium greater than about 15 per cent but less than about 35 per cent. I also prefer to employ the three-component gas filling at a total pressure in the range of about 10 to 25 mm. Hg at room temperature (about 80° F.).

For a further understanding of my invention reference may be had to the accompanying drawing wherein Figs. 1 and 2 are elevations showing, by way of example, two forms of glow lamps in which the gas filling composition comprising my invention may be employed.

Referring to Fig. 1, the lamp shown therein comprises a bulb or envelope 1 of glass which is permeable to the ultraviolet radiations (mainly about 3200-3800 Angstroms) emitted by the discharge therein. The bulb contains a pair of activated "cold" electrodes 2 of the so-called "split acorn" type and which are supported by a pair of lead-in wires 3 which are sealed through a conventional glass stem tube 4 sealed to the end of the bulb 1. The electrodes 2 may consist of sheet nickel of generally one-quarter hemispherical shape and they are activated with a coating 5 of electron emitting material, preferably alkaline earth materials such as barium and strontium carbonates which are broken down, in known manner, to form the corresponding oxides. The inner surfaces of the electrodes 2 are preferably coated in known manner with an aluminum getter paint. The bulb 1 is then filled through the conventional exhaust tube 6 with the gas composition comprising my invention. The tube 6 is then sealed and the electrodes are activated by a discharge therebetween of high potential, high frequency electrical energy having a steep wave front.

Lamps of the type shown in Fig. 1 are usually operated, in series with a ballast resistor, from an alternating current source of 105-125 volts. The particular lamp illustrated is designed to op-

erate at an energy consumption of about $\frac{1}{4}$ watt with a current of 2 milliamperes. The following table illustrates the life performance of such lamps containing various proportions of the argon-helium-nitrogen filling, and the relative ultraviolet output (UV) and alternating-current breakdown-voltage (BD) obtained thereby.

Percent			0 Hrs.		120 Hrs.		528 Hrs.		792 Hrs.		1,228 Hrs.	
Ar	He	N ₂	UV	BD	UV	BD	UV	BD	UV	BD	UV	BD
85	0	15	84	89	83	83	54	82	66	97	--	--
77	10	13.1	78	80	84	84	82	79	66	97	--	--
69	19.6	11.3	71	89	76	88	83	86	83	91	69	88
61	29.6	9.4	83	83	77	81	80	77	75	95	53	95
53	39.2	7.6	106	84	88	89	97	89	104	105	--	--
35.3	80.0	3.5	95	87	80	97	84	85	77	110	--	--

The optimum composition of 65 per cent argon, 25 per cent helium and 10 per cent nitrogen resulted in a useful ultraviolet output, to the same degree of depreciation, for a period approximately three times as long as with otherwise similar lamps containing only the two-component gas mixture of argon and nitrogen.

The lamp shown in Fig. 2 comprises a tubular glass bulb 1 of small size, for example approximately $\frac{1}{4}$ inch diameter, and an over-all length of about $1\frac{1}{8}$ inches. The bulb 1 contains a pair of electrodes 8, of nickel wire, for example, which are mounted on lead-in wires 9 extending through a flattened press portion 10 at the end of the bulb 1. The electrodes 8 may be activated with a coating 11 of alkaline earth materials as described in connection with the lamp of Fig. 1. Such lamps are designed to operate at an energy consumption of about $\frac{1}{25}$ watt from a source of 105-125 volts at a current of .3 millampere.

It is virtually impossible to make such lamps with the usual gas filling of argon and nitrogen due to cleaning up of the nitrogen. However, by employing the three-component gas mixture of argon, helium and nitrogen in accordance with my invention such lamps are operable for a useful life in excess of 100 hours. With the optimum gas filling of 65 per cent argon, 10 per cent nitrogen and 25 per cent helium, at a pressure of about 15 mms. at room temperatures, such lamps start at about 70 volts on an alternating current source and at about 98 volts on a direct current source.

What I claim as new and desire to secure by Letters Patent of the United States is:

1. An ultraviolet-emitting gaseous electric glow discharge lamp comprising a sealed light-transmitting envelope having electrodes sealed therein and spaced relatively closely for a glow discharge therebetween and containing a fixed gas filling consisting of substantial proportions of argon, nitrogen and helium at a total pressure in the range of about 10-25 mm.

2. An ultraviolet-emitting gaseous electric glow

discharge lamp comprising a sealed light-transmitting envelope having electrodes sealed therein and spaced relatively closely for a glow discharge therebetween and containing a fixed gas filling consisting of substantial proportions of argon, nitrogen and helium at a total pressure in the range of about 10-25 mm., the nitrogen

20 constituting, by volume, about 5 to 15 per cent of the mixture and the helium being greater than 5 per cent of the total.

3. An ultraviolet-emitting gaseous electric glow discharge lamp comprising a sealed light-transmitting envelope having electrodes sealed therein and spaced relatively closely for a glow discharge therebetween and containing a fixed gas filling consisting of substantial proportions of argon, nitrogen and helium at a total pressure in the range of about 10-25 mm., the nitrogen 25 constituting, by volume, about 5 to 15 per cent of the mixture and the helium between 5 and 80 per cent with the remainder argon.

4. An ultraviolet-emitting gaseous electric glow discharge lamp comprising a sealed light-transmitting envelope having electrodes sealed therein and spaced relatively closely for a glow discharge therebetween and containing a fixed gas filling consisting of argon, nitrogen and helium at a total pressure in the range of about 10-25 mm. and in proportions, by volume, in the range of about 5 to 15 per cent nitrogen, 15 to 35 per cent helium and the balance argon.

5. An ultraviolet-emitting gaseous electric glow discharge lamp comprising a sealed light-transmitting envelope having electrodes sealed therein and spaced relatively closely for a glow discharge therebetween and containing a fixed gas filling consisting of argon, nitrogen and helium at a total pressure in the range of about 10-25 mm. and in proportions, by volume, of approximately 65 per cent argon, 25 per cent helium and 10 per cent nitrogen.
